[57] CLAIM

The ornamental design for a pair of crimping pliers, as shown.

DESCRIPTION

FIG. 1 is an elevation of a pair of crimping pliers showing my new design;

FIG. 2 is a side view taken as indicated by the arrow A in FIG. 1;

FIG. 3 is an elevation of the said crimping pliers but taken from the opposite side to FIG. 1; and

FIG. 4 is a side view taken as indicated by the arrow B in FIG. 3.

Fig. 3.

Fig. 4.
